UNITED STATES PATENT OFFICE.

WILLIAM WOLFE, OF ALSACE TOWNSHIP, PENNSYLVANIA, ASSIGNOR OF ONE-HALF
TO FRED W. SHIPE, OF TEMPLE, PENNSYLVANIA.

FOLDING PAPER BOX.

Application filed April 2, 1927. Serial No. 180,547.

This invention aims to provide a box which may be fashioned cheaply, the box being strong in construction, and presenting, when closed, the appearance of an article that is covered by a folded wrapper.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in plan, the blank out of which the cover of the box is made;

Figure 2 is a plan wherein the blank of Figure 1 is shown partly folded;

Figure 3 is a perspective showing the cover partly folded;

Figure 4 is a perspective wherein the cover is shown in a further step of completion;

Figure 5 is a transverse section of the completed cover;

Figure 6 is a longitudinal section of the completed cover;

Figure 7 is a view similar to Figure 3, but showing the base portion of the box, parts being broken away;

Figure 8 is a fragmental perspective showing a portion of the completed base of the box.

The blank out of which the cover C is fashioned, is made of pasteboard, or any other suitable material. The blank is shown in Figure 1 and comprises a rectangular body 1 having end flaps 2, disposed opposite to each other, and a first side flap 3 and a second side flap 4 disposed opposite to each other. The first side flap 3 has a first extension 5, the area of which is about equal to the area of the body 1. The side flap 4 has a second extension 6 which is of much less area than the extension 5. The side flaps 3 and 4 have terminal wings 7. Slits 8, disposed opposite to each other, extend inwardly from the edges of the end flaps 2.

There are slits 9 in the transverse edges of the extension 5, and these slits define fingers 10. In the longitudinal edge of the extension 5 there are slits 11 forming a finger 12. Tongues 14 may be formed in the extension 5, near to its longitudinal edge. The extension 6 has openings 15 located opposite to the tongues 14. The longitudinal edges of the body 1 are shown at 16, and the transverse edges of the body 1 appear at 17. On the end flaps 2 there are lines 18 that connect the inner ends of the slits 8. On the end flaps 2 there are lines 19 alined with the ends 20 of the wings 7. Lines 21 on the end flaps 2 converge from the outer ends of the lines 17 and 19 to the inner ends of the slits 8. The line 22 of juncture between the flap 3 and its extension 5 is alined with the longitudinal edges 23 of the adjacent wings 7. The line 24 of juncture between the extension 6 and the side flap 4 is alined with the edges 23 of the corresponding wings 7. A line 25 extends across the flap 4 and the adjacent wings 7 in parallel relation to the line 24 and is located midway of the width of the flap 4. A line 26 extends across the flap 3 and the corresponding wings 7 in parallel relation to the line 22 and is located midway of the width of the flap 3. Lines 27 mark the juncture between the side flaps 3 and 4 and the wings 7. It is understood that the elements referred to as "lines" need not actually be inscribed on the blank. They may be produced merely in the folding operation, but they have been described and alluded to as "lines" to the end that the operation of folding the blank to form the cover C may the more easily be described.

The flap 3 is folded together along the line 26 and turned up along the line 16 to form one side wall of the cover, and the extension 5 is turned up along the line 22 as in Figure 1. The flap 4 is folded together along the line 25 and turned up along the line 16 to form the opposite side wall of the cover, the extension 6 being folded along the line 24 to overlie the body 1. The wings 7 (having been folded together along the lines 26 and 25) are turned inwardly along the lines 27, at right angles to the sides of the cover, to form the ends of the cover, and the folded wings 7 are telescoped as at 28. The corners 29 formed in the end flaps 2 by the slits 8 are bent along the lines 21 and are overlapped upon the flaps 2, as shown in

Fig. 3, and the cover, as thus far completed, appears as shown in that figure. The end flaps 2 then are folded at 18 over the edges 25 of the wings 7, and the inner parts of the wings 7 are bent along the lines 19 to form flanges 30 that overlap the body 1, as shown at the right hand end of Fig. 4. The extension 5 is turned down parallel to the body 1, in overlapped relation to the flanges 30 and the extension 6; the finger 12 is engaged beneath the extension 6, the tongues 14 on the extension 5 and engaged in the openings 15 of the extension 6, and the fingers 10 on the extension 5 are engaged beneath the flanges 30 on the terminal wings 7.

In Figures 7 and 8 of the drawings, the base B of the box is shown, the base being adapted to be used in connection with the cover C. In Figures 7 and 8, parts hereinbefore described have been designated by numerals previously used, with the suffix "a." The modification consists in omitting the slits shown at 8 in Figure 1, and the folding at 21 in Figure 3, which produces the corners 29. The construction shown at 8—21—29 is employed, in connection with the cover C, in order that the outside of the box may have the appearance of being closed within a piece of paper or other cover that is folded, the lines 21 in the completed article being noted at this point. The base B of the box is concealed for the most part

within the cover C and there is no occasion for having, in the base B, the converging lines shown at 21.

Three means are provided for holding down the first extension 5 on the body 1, namely, the finger 12, the tongues 14, and the fingers 10; but it will be understood that any one of these instrumentalities may be used to the exclusion of the other.

What is claimed is:—

A box member including a base the side walls of which include inner layers which have extensions that are overlapped on the base and on each other, there being double-layer end walls which are connected to the extremities of the side walls, the end walls being located at right angles to the side walls, and being telescoped into each other, there being wings prolonged upon the outer surfaces of the end walls and connected to the extremities of the base, the wings being supplied with transverse slits which define corners, the corners being turned under, to cause the wings to taper both inside and outside of the box member, the wings being extended upon the outer surfaces of the end walls and being folded across the edges of the end walls.

In testimony that I claim the foregoing as my own, I have hereto affixed my signature.

WILLIAM WOLFE.
